ROLL WINDER FOR PAPERMAKING AND THE LIKE

Henry R. Patterson, Jr., West Chester, Pa., assignor to Beloit Eastern Corporation, Downingtown, Pa., a corporation of Delaware

Filed Aug. 12, 1964, Ser. No. 81,261

Term of patent 14 years

(Cl. D55—1)

The dominant features of my design reside in a portion shown in full lines. The top view of my design is substantially planar.

I claim:

The ornamental design for a roll winder for papermaking and the like, as shown and described.
